12 Claims. (Cl. 84—1.01)

ABSTRACT OF THE DISCLOSURE

Sound reproducing system for electric organ having a multiplicity of pipes of different lengths and diameters projecting from a wall, with loud speakers producing sound on the opposite side of the wall. A baffle of substantial thickness has slots therein for coupling each speaker to a plurality of pipes. Tremolo and other effects can be provided by modulating the signal applied to the speakers and/or by movable mechanical means in the path of the sound waves. The pipe speaker assembly may be utilized with a bass speaker and/or a rotor speaker.

This invention relates to a sound reproducing system and more particularly to such a system for an electronic organ and which includes one or more sound reproducers and resonant pipes operative to generate tones and sound effects similar to those produced by a pipe organ.

Arrangements have heretofore been proposed using pipes in conjunction with conventional speakers to enhance tonal qualities, but such arrangements have been of quite limited value particularly with respect to efficiency of reproduction, with respect to the number of pipes which can be used, and with respect to the attainment of a satisfactory balance in the production of tones of various frequencies.

The present invention was evolved with the general object of overcoming such disadvantages of prior systems and with the specific object of providing a sound reproducer for an electronic organ system using pipes to produce tones and sound effects similar to those produced by a pipe organ, while avoiding the high cost, large size and other disadvantages of the pipe organ.

According to an important feature of this invention, electrical signals of selected frequencies and harmonic contents, such as produced by known electronic organ circuitry, are applied to a plurality of speakers, each of which is efficiently coupled directly to the ends of a limited number of pipes, with the pipes being of various lengths such as to resonate at frequencies corresponding to the fundamental and/or harmonic frequency components of the applied signals. With this arrangement, it is possible to utilize pipes in numbers sufficient to obtain an extended tonal range but with a balanced excitation such as to produce an effect similar to that produced by the pipe organ. Due to the resonance of the pipes, the build-up of sound is gradual and likewise the decay is gradual, with a softened attack and release effect like that obtained with the pipe organ, but not obtained with conventional speakers. An effective dispersion of sound is produced without the directional effects of conventional speakers. At the same time, the pipes do not require tuning, since the sound is produced by the speakers. Further, the reproducer is relatively simple and inexpensive in construction and does not require the blower and other equipment of the conventional pipe organ.

An important feature of the invention relates to a coupling arrangement for obtaining an efficient and balanced excitation of a plurality of pipes directly from a speaker. In accordance with this feature, the speaker is mounted on the inside with respect to a wall having openings into which the inner ends of a plurality of pipes are secured,

and means are provided projecting inwardly from the wall toward the speaker to reduce the volume and to define close coupling means which efficiently channels and distributes the sound waves from the speaker into the ends of the pipes.

In accordance with a specific feature of the invention, the coupling is provided by a baffle of substantial thickness on the inner surface of the wall, the baffle having a plurality of slots therein each aligned with openings disposed in a row, with the sound being channelled and distributed from the speaker through the slots into the ends of the pipes.

According to another important feature of the invention, the pipe ends are secured in openings extending along one wall of an elongated enclosure, with the speakers being mounted within the enclosure in spaced relation therewith. With this arrangement, a compact sound reproducer is provided which can be readily disposed against a wall, or on top of a console.

According to a specific feature of the invention, elliptical speakers are used with an arrangement of pipes such as to obtain close coupling and high efficiency, with each speaker being effective to supply sound waves into several pipes.

A further important feature of the invention relates to the modulation at a sub-audible rate of the amplitude of sound developed in the pipes, to produce a tremolo, chortle effect, or the like. This feature is important in that the same slow build-up and decay of the sound is produced as with a conventional pipe organ while using energization by electrical signals. The same effect is not obtainable with the conventional speaker systems of electronic organs. In a preferred embodiment of the invention, the modulation means comprises electronic means for modulating the amplitude of electrical signals applied from amplifier means to the speakers. In other embodiments, the modulation means comprises mechanical means in the path of sound waves transmitted from the speaker through the pipes for varying the transmission of the waves.

Still another feature of the invention relates to piercing of pipes to "open" the sound, produce natural "wind" and to induce other harmonics. A more specific feature relates to the use of piercing to enable a pipe having a closed end to emit sound and to produce the desired effects. With this arrangement tones an octave lower can be produced with a pipe of the same length.

This invention contemplates other and more specific objects, features and advantages which will become more fully apparent from the following detailed description taken in conjunction with the accompanying drawings which illustrate preferred embodiments and in which:

FIGURE 1 is a perspective view of a sound reproducer in the form of a pipe speaker constructed according to the principles of this invention;

FIGURE 2 is a top plan view of the pipe speaker of FIGURE 1;

FIGURE 3 is a vertical sectional view taken substantially along the line III—III of FIGURE 2;

FIGURE 4 is a horizontal sectional view taken substantially along the line IV—IV of FIGURE 3;

FIGURE 5 is a circuit diagram of an electronic organ system using the pipe speaker of FIGURES 1—4;

FIGURE 6 is a diagrammatic view of a modification of the speaker of FIGURE 1 using an oscillating plate for controlling supply of sound into the ends of the pipes;

FIGURE 7 is a diagrammatic view of another modification similar to that of FIGURE 6 but using a rotating baffle;

FIGURE 8 is a diagrammatic view of still another modification using an oscillating plate at the upper ends of pipes;

FIGURE 9 illustrates a portion of a speaker similar to FIGURE 1, but with a modified construction having holes in the pipes; and

FIGURE 10 is a view similar to FIGURE 9, but illustrating a modification using holes in connection with closed pipes.

Referring to FIGURES 1 to 4, reference numeral 10 generally designates a sound reproducer constructed according to the principles of this invention, designed for use in an electronic organ system. The reproducer 10 comprises an elongated generally rectangular enclosure 11 having a top wall 12, a bottom wall 13, a front wall 14, a back wall 15 and end walls 16 and 17. Preferably, the walls are of wood with dove-tailed and glued joints.

In accordance with this invention, the top wall 12 is formed with two generally parallel rows of openings therein, a front row of openings 19 and a rear row of openings 20, into which are tightly fitted the lower ends of a multiplicity of vertical pipes of various lengths arranged in a front row of pipes 21 and a rear row of pipes 22. The 20 openings 19 and 20 are preferably provided with reduced diameter lower end portions defining annular shoulders for receiving the lower ends of the pipes 21 and 22 thereagainst (FIG. 3), to prevent the pipes from being pushed downwardly into the enclosure 11.

Various arrangements of the pipes are possible. In the illustrated reproducer, there are twenty-eight of the pipes 21 in the front row arranged with the longer pipes on the outside, decreasing in length toward the center, while there are twenty-one of the pipes 22 in the back row with shorter pipes on the outside increasing in length toward the center, the pipes in the center of the back row being longer than those on the ends of the front row. Thus the arrangement is generally symmetrical, but it is not exactly symmetrical because no two pipes have the same lengths. Instead, their lengths are stepped to be resonant at different frequencies of an extended range, corresponding to notes in the middle and upper frequency range of an electronic organ. The pipes are also not of uniform diameters, the shorter pipes having smaller diameters.

By way of example and not by way of limitation, the overall length of the illustrated enclosure 11 may be forty-one and five-eighths inches and the dimensions of the pipes and other components may be proportioned as illustrated.

To provide additional support for the longer pipes, a plate 23 is provided which is supported by spacer sleeves 24 in spaced relation above the top wall 12, having openings for all of the pipes 22 of the rear row and having openings for pipes at the opposite ends of the front row, the plate having a cut-out portion 25 so as not to receive the shorter pipes at the center of the front row, which do not require the additional support.

In the illustrated embodiment, four oval or elliptical speakers 27, 28, 29 and 30 are provided in the enclosure 11 in spaced relation therealong, each arranged to project sound into the lower ends of a plurality of pipes. Thus the left-hand speaker 27 is positioned to project sound into the ends of the first five pipes of the front row and the first five pipes of the rear row (starting from the left as viewed in the drawings); the second speaker 28 is positioned to project sound into the next nine pipes of the front row and the next five pipes of the rear row; the third speaker 29 is arranged to project sound into the next eight pipes of the front row and the next five pipes of the rear row; and the fourth speaker 30 is arranged to project sound into the last six pipes of the front row and the last six pipes of the rear row.

With this arrangement, a relatively large number of pipes can be used with a relatively small number of speakers and yet a balanced performance is obtained over the entire frequency range. The elongated form of the enclosure and the use of oval speakers are important in that the pipes are in side-by-side relation with none of the pipes being surrounded by other pipes, thereby to mini-

mize interference effects. At the same time, the unit can be readily placed on top of an organ console or against a wall. A further advantage is in appearance, with the generally symmetrical arrangement of pipes being that associated with a conventional pipe organ.

According to an important feature of the invention, means are provided for increasing the closeness of coupling between the speakers and the pipes to produce maximum efficiency and to allow a maximum number of pipes to be used with a given tone area, while obtaining balanced excitation of the pipes. In accordance with this feature, a baffle member 32 (FIG. 4), preferably of wood, is interposed between the top wall 12 and the speakers 27-30 and is provided with a pair of slots for each speaker. These slots are aligned with the front and rear rows of top wall openings and expose the pipes to the corresponding speakers. In particular, slots 33 and 34 are provided above the speaker 27 respectively aligned with the first five front row openings 19 and the first five rear row openings 20. Similarly, front and rear slots 35 and 36 are provided above speakers 28, front and rear slots 37 and 38 are provided above the speaker 29 and front and rear slots 39 and 40 are provided above the speaker 30.

With this arrangement, a chamber of small volume is provided above the speaker cone, and the acoustical compliance is very small, while the slots serve as coupling sections to smoothly direct the sound waves into the ends of the pipes. As a result very tight acoustical coupling is obtained to produce high efficiency while also obtaining a balanced excitation of the pipes. The use of the slots is particularly advantageous in that it facilitates use of the elongated enclosure and multiple oval speaker features, with the pipes arranged in continuous rows.

According to a specific feature of the invention partition members 41, 42 and 43 are provided to cooperate with the end walls 16 and 17 in defining four separate back chambers for the speakers 27-30, thus minimizing the possibility of interference effects.

FIGURE 5 is a circuit diagram of a system for energizing the speakers 27-30. In this system, a circuit point 50 is connected through speakers 27 and 28 in series to ground and through speakers 29 and 30 in series to ground. Circuit point 50 is connected to the output of an amplifier 51 having an input normally connected through a selector switch 52 to the junction between resistors 53 and 54. Resistor 53 being connected to ground and resistor 54 being connected through a capacitor 55 to a selector switch 56 for selective connection to output terminals 57 and 58 of an electronic organ signal generator 60. A speaker 61 of a bass speaker enclosure 62 is connected through a filter including capacitor 63 and resistor 64 to the selector switch 56.

Resistors 53 and 54 and capacitor 55 form a high pass filter for applying frequency components above a crossover frequency to the pipe speakers 27-30 while capacitor 63 and resistor 64 form a low pass filter for applying frequency components below the crossover frequency to the bass speaker 61. With this arrangement, the pipe speaker can produce frequency components in the middle and upper frequency range, and the lower frequency components are produced by the bass speaker enclosure. This is highly desirable in that the lowest frequency to be reproduced by the pipe speaker can be relatively high, thus reducing the required length of the longest pipe, and the required number of pipes so that the unit can be of relatively small size. At the same time, excellent quality of sound is obtained, approaching that of a pipe organ, even with the lower frequency tones. An important contributing factor is the fact that the pipes of the pipe speaker resonate at harmonics of the lower frequency tones, and a pronounced pipe organ effect is obtained with such tones.

The overall efficiency of the reproducer 10 is substantially less than that of a conventional reproducer, because considerable energy is consumed in dispersing the sound

through the pipes. Accordingly, the amplifier 51 is normally required, as when the system is used for producing diapason tones. In other circumstances, however, the amplifier 51 may not be required, particularly in producing flute tones, which are more sinusoidal in nature than the complex voices, and the pipes do not require much power to be effective. Thus, with switch 56 connected to the terminal 58, which may be assumed to be the output of the flute channel, the switch 52 may be operated to connect to the output of the high pass filter directly to the pipe speaker 10.

The speaker system may also incorporate a rotor speaker 65 in an enclosure 66, which may be connected through a selector switch 67 to the circuit point 50. The combination of the rotor speaker with the pipe speaker is highly effective in that although the rotor speaker generally produces good "ethereal" and "celeste" effects, the constant moving of the rotor robs the flute tone of its presence and can cause the organist difficulty in playing fast passages on the high flute pitches. The pipe speaker does not destroy the moving, life-like quality that the low rotor produces, but adds the life and pipe-like quality to the top of the flute tones.

As above discussed, the pipes, being resonant, cause a slow build-up and a slow decay of tones which is highly desirable in achieving the same effect as obtained with a pipe organ. It is found that this effect is also highly advantageous in tremolo or chortle effects, or the like. In the illustrated system, the tremolo effect is obtained in a very simple manner electronically, by connecting a tremolo oscillator 68 to the amplifier 51, through switch 69. Thus, by merely modulating the output of the amplifier 51 at a low frequency, the tremolo effect is readily obtained, and it is enhanced by the slow build-up and decay characteristics which are obtained with the resonant pipes.

FIGURE 6 diagrammatically illustrates a modified arrangement for mechanically producing the tremolo or chortle effect. In this arrangement, a plate 70 having a form similar to that of the baffle plate 32 and having slots therein aligned with the slots of the baffle plate, including slots 71 and 72 corresponding to slots 39 and 40 of the baffle plate 32, is interposed between the baffle plate 32 and the top wall 12 of the enclosure. The plate 70 is oscillated at a low frequency by an oscillating mechanism 73, in a direction transverse to the direction of the slots.

FIGURE 7 diagrammatically illustrates another modified arrangement for mechanically producing tremolo or chortle effects, wherein a plate 74 is provided for substitution for the baffle plate 32, the plate 74 having a pair of slots 75 and 76 for extending under the pipe ends, with rotors 77 and 78 being provided in these slots 75 and 76, and being rotated by a suitable rotating mechanism 79.

FIGURE 8 illustrates still another modified arrangement for producing tremolo or chortle effects, wherein pipes 80 are installed on an enclosure 81, having speakers therein and constructed in the same manner as the enclosure 11, but with the pipes 80 being arranged so that the downwardly inclined plate 82 is aligned in co-planer relation with the upper ends of the pipes. As diagrammatically illustrated, a plate 83 having openings 84 corresponding to the openings in the ends of the pipes may be disposed against the plate 82, and may be oscillated by an oscillating mechanism 85 to produce the desired effect.

FIGURE 9 illustrates a modified arrangement wherein a front row of pipes 87 and a rear row of pipes 88 are substituted for the front row of pipes 21 and the rear row of pipes 22 of the reproducer 10 of FIGURES 1 and 4. The pipes may be identical to those of the reproducer 10, except they have holes 89 and 90 therein positioned approximately midway between the lower and upper ends thereof. The openings preferably have a size on the order of from $\frac{1}{64}$ to $\frac{1}{8}$ of an inch. Such openings produce increased harmonics, predominately odd harmonics since a clarinet-like tone is added to the fundamental resonance.

The openings also produce "rushing wind" and "whistle blowing" sounds.

FIGURE 10 illustrates an arrangement which is the same as that of FIGURE 9, except that caps 91 and 92 are placed on the upper ends of the front and rear rows of pipes 87 and 88, to provide stopped or closed pipes. The closed pipes resonate at a frequency lower than that obtained with the open pipes. Thus a lower range of frequency of operation may be obtained, or in the alternative, the pipes may be made shorter to obtain the same range of frequency. The provision of the openings 89 is necessary to allow emanation of sound from the pipes, and at the same time, the openings produce additional harmonics, as may be desired.

It will be understood that modifications and variations may be effected without departing from the spirit and scope of the novel concepts of this invention.

We claim:

1. A sound reproducer including in combination, a wall having a plurality of openings therein arranged in a row, a plurality of pipes each having an end secured in one of said openings to project outwardly from said wall, a baffle of substantial thickness on the inner surface of said wall having a plurality of slots therein aligned with the openings in said row, and a plurality of speakers on the inward side of said baffle and each projecting sound through one of said slots into the ends of a plurality of said pipes, each of said slots defining coupling means effective to channel and distribute sound from one of said speakers into the ends of a plurality of said pipes.

2. In a sound reproducer for use with an electronic organ, a wall having openings therein arranged in a row, a plurality of pipes of varying lengths each having an end disposed in one of said openings to project outwardly from said wall, a baffle of substantial thickness on the inner side of said wall having a slot therein aligned with the openings in said row, and an oval speaker behind said wall having its longer dimension aligned with the row of openings for projecting sound through said slot and through all of said openings into the ends of said pipes, said slot defining coupling means effective to channel and distribute sound from said speaker into the ends of said pipes.

3. In a sound reproducer for use with an electronic organ, a wall having openings therein arranged in substantially parallel rows with a plurality of openings in each row, a plurality of pipes each having an end secured in one of said openings to project outwardly from said wall, a baffle of substantial thickness on the inner surface of said wall having a plurality of substantially parallel elongated slots therein each aligned with the openings in one of said rows, and a speaker on the inward side of said baffle for projecting sound through said slots and the ends of said pipes, said slots defining coupling means effective to channel and distribute sound from said speaker into the ends of said pipes.

4. A sound reproducer including in combination, a wall having openings therein arranged in two rows with at least three openings in each row and with the spacing between rows and the spacings between openings of each row being approximately equal, a plurality of pipes of varying lengths each having an end disposed in one of said openings to project outwardly therefrom, a baffle of substantial thickness on the inner side of said wall having a plurality of slots therein each aligned with the openings in one of said rows, and a plurality of oval speakers on the inward side of said baffle having the longer dimensions thereof aligned with said slots for projecting sound therethrough and through all of said openings into the ends of said pipes, each of said slots defining coupling means effective to channel and distribute sound from one of said speakers into a plurality of said pipes.

5. In a sound reproducer for use with an electronic organ, an elongated enclosure having a multiplicity of

openings arranged in rows along one wall thereof, a multiplicity of pipes of varying lengths and diameters having inner ends secured in said openings to project in parallel relation from said wall, a plurality of speakers mounted within said enclosure in spaced relation therealong each arranged to project sound through a plurality of said openings in at least two rows and into said pipes secured therein, and a plurality of partitions within said enclosure in spaced relation therealong and disposed between said speakers to define a separate chamber for each of said speakers.

6. A sound reproducer including in combination, wall means having a multiplicity of openings therein, a multiplicity of pipes of varying lengths each having an inner end secured in one of said openings to project outwardly from said wall means, a plurality of speakers on the inward side of said wall means, baffle means between said wall means and said speakers and having slots therein coupling sound from said speakers to said inner ends of said pipes, and means completely closing the outer ends of at least a plurality of said pipes, said last-mentioned plurality of pipes having openings therein intermediate the inner and outer ends thereof for emanation of sound from said pipes.

7. A sound reproducing system for reproducing signals at selected frequencies, including in combination, a bass speaker unit, a pipe speaker unit, low pass and high pass filter means for respectively applying signals to be reproduced respectively to said bass speaker unit and said pipe speaker unit, said pipe speaker unit comprising wall means having a multiplicity of openings therein, a multiplicity of pipes each having an inner end secured in one of said openings to project outwardly from said wall means, and speaker means mounted inwardly from said wall means and arranged to project sound into said inner ends of a plurality of said pipes.

8. A system as defined in claim 7 including a booster amplifier for applying signals to said pipe speaker unit.

9. A sound reproducing system for an electronic organ including in combination, a pipe speaker unit, a rotor speaker unit, means for applying signals to both said speaker units, said pipe speaker unit comprising wall means having a multiplicity of openings therein, a multiplicity of pipes each having an inner end secured in one of said openings to project outwardly from said wall means, and a plurality of speakers mounted inwardly from said wall means and each arranged to project sound into the inner ends of a plurality of said pipes.

10. In a sound reproducer for an electronic organ, wall means having a multiplicity of openings therein, a multiplicity of pipes of varying lengths each having an inner end secured in one of said openings to project outwardly from said wall means, speaker means arranged to project sound into said inner ends of said pipes, and oscillating mechanical means adjacent to the outer ends of said pipes and having a portion extending in the path of sound therefrom for mechanically modulating the sound output therefrom.

11. A sound reproducer including in combination, wall means having a multiplicity of openings therein, a multiplicity of pipes of varying lengths each having an inner end secured in one of said openings to project outwardly from said wall means, speaker means arranged to project sound into said inner ends of said pipes, and oscillating mechanical means interposed between said speaker means and the inner ends of said pipes and having a portion extending in the path of the sound for mechanically modulating the sound applied to said pipes.

12. A sound reproducer including in combination, a wall having a plurality of openings therein arranged in a row, a plurality of pipes each having an end secured in one of said openings to project outwardly from said wall, a baffle of substantial thickness on the inner surface of said wall having a slot therein aligned with the openings in said row for applying sound to said ends of said pipes, and an additional baffle adjacent to the first-mentioned baffle and having a slot aligned with the slot therein, said additional baffle being movable in a direction transverse to said slot to modulate the sound applied to said ends of said pipes.
